Horace Weston

United States Patent Office.

HORACE WESTON, OF BOSTON, MASSACHUSETTS.

Letters Patent No. 65,712, dated June 11, 1867.

IMPROVED SKYLIGHT.

The Schedule referred to in these Letters Patent and making part of the same.

TO ALL WHOM IT MAY CONCERN:

Be it known that I, HORACE WESTON, of Boston, in the county of Suffolk, and State of Massachusetts, have invented certain improvements in Skylights for Buildings, &c., of which the following is a full, clear, and exact description, reference being had to the accompanying drawings, making part of this specification, in which—

Figure 1 is a plan of the sash of a skylight having my improvements applied thereto.

Figure 2 is a transverse section on the line $x-x$ of fig. 1.

Figure 3 is a longitudinal section on the line $y-y$ of fig. 1.

Figure 4 is a transverse section of one of the bars of the skylight.

With the ordinary skylight sash as at present constructed, as soon as the putty which confines the glass becomes cracked and loosened, the water is admitted and runs down the bars on the inside into the room or apartment, frequently causing much damage.

My invention has for its object to overcome this difficulty, and consists in forming a groove or gutter on each side of the bars and at the sides of the sash below the shoulder on which the edge of the glass rests, so that any water which may pass through will fall into the grooves and be conducted outside; and my invention also consists in so cutting away or forming the upper surface of the bottom rail of the sash, that any moisture which may collect on the inner surface of the glass will run down and be conducted into the grooves, and thence pass outside instead of dropping down, as has heretofore been the case.

To enable others skilled in the art to understand and use my invention, I will proceed to describe the manner in which I have carried it out.

In the said drawings, A is the sash of the skylight, and B B the bars which support the glass, C. These bars (which extend down to the bottom of the sash) are of the form in cross-section shown in figs. 2 and 4, being provided with a groove or gutter, a, on each side beneath the shoulder b, on which the edge of the glass rests; and it will be seen that in the event of the putty becoming cracked and loosened, any water which may pass through between the bars and the glass will fall down into the gutters a and be conducted outside the building at the points 5 instead of falling into the apartment. A similar groove, c, is also formed at each side of the sash, so as to lead the water away at these points. The lower portions of the grooves a c, communicating with the external air, also form openings which serve to ventilate the apartment. The bottom rail, D, of the sash, is cut away at d, leaving spaces, e, between the glass and the rail, as seen in figs. 2 and 3, so that any moisture which may collect on the inner surface of the glass will run down, and striking the inclined edges 6, be conducted into the grooves a c, whence it will pass out as before described, instead of dropping into the apartment, as would be the case if the glass came in contact with the upper edge 7 of the rail D, as is the case in the ordinary sashes now in use.

My improvements may be applied to wooden sashes, or to those formed of metal, being particularly well adapted for the latter, where the putty soon becomes cracked and loosened from the expansion and contraction of the metal, caused by variations of the temperature. A sash constructed as above described may be furnished at a moderate cost, and will entirely prevent water from passing through into the apartment, thus avoiding the liability of damage from this cause—an event of not unfrequent occurrence with sashes as at present constructed.

Claim.

What I claim as my invention, and desire to secure by Letters Patent as an improvement in sashes for skylights, is—

Forming grooves or gutters a c in the bars B, and at the sides of the sash, substantially as and for the purpose described.

I also claim so forming or cutting away the upper surface of the bottom rail D, that the moisture will run down into the grooves a c, substantially as set forth.

HORACE WESTON.
